59,975.

Specification for Design.

Patented Dec. 13, 1921.

Application filed June 1, 1921. Serial No. 474,277. Term of patent 7 years.

To all whom it may concern:

Be it known that I, TOKUJI NAKAMURA, a subject of the Emperor of Japan, residing at San Leandro, in the State of California, have invented a new, original, and ornamental Design for a Motor-Fan, of which the following is a specification, reference being had to the accompanying drawing, forming part thereof.

Figure 1 is a view in front elevation of a motor fan embodying my design.

Fig. 2 is a rear elevational view of a motor fan embodying my design, and

Fig. 3 is a side elevational view of a motor fan embodying my design.

I claim:

The ornamental design for a motor fan, as shown.

TOKUJI NAKAMURA.
